(57) **CLAIM**

We claim the ornamental design for a combined fishing lure holder and case, substantially as shown and described.

DESCRIPTION

FIG. 1 is a perspective view of the fishing lure holder and case of the present invention with foam lure holders.

FIG. 2 is a front or inside view of the holder and case.

FIG. 3 is a back or outside view of the holder and case.

FIG. 4 is a top edge elevation view of the holder and case.

FIG. 5 is a bottom edge elevation view of the holder and case.

FIG. 6 is a left side edge elevation view of the holder and case.

FIG. 7 is a right side edge elevation view of the holder and case.

FIG. 8 is a perspective view of the fishing lure case of the present invention in an open configuration, having the same case as in FIGS. 1-7 but without the foam lure holders with dashed lines representing stitching along various parts of the case.

FIG. 9 is a front or inside plane view of the case.

FIG. 10 is a back or outside plane view of the case.

FIG. 11 is a top edge elevation view of the case.

FIG. 12 is a bottom edge elevation view of the case.

FIG. 13 is a left side elevation view of the case; and,

FIG. 14 is a right side elevation view of the case.
